UNITED STATES PATENT OFFICE

LEOPOLD KAHN, OF NEW YORK, N. Y.

DESIGN FOR HARDWARE ORNAMENTATION.

SPECIFICATION forming part of Design No. 22,604, dated July 11, 1893.

Application filed April 13, 1893. Serial No. 470,250. Term of patent 3 $\frac{1}{4}$ years.

To all whom it may concern:

Be it known that I, LEOPOLD KAHN, of the city, county, and State of New York, have invented a new and original Design for Hardware Ornamentation, of which the following is a full, clear, and exact description.

Reference is to be had to the accompanying drawing forming a part of this specification, in which the figure is a plan view of a strip of metal showing my design.

The leading feature of my design is the scalloped and fringe-like borders, and the open curved and fern-like figures arranged between and connecting the borders. The metal is of an open structure and comprises parallel borders each formed of a braid-like

figure having on its outer side a scalloped leafy or flower-like fringe, and the body portion of the metal, which is arranged between the two borders and which is made up of a series of connecting fern-like figures, these being curved into the form of scrolls. The body portion of the metal swells outward slightly between the borders, as shown in cross section.

I claim—

The design for hardware ornamentation, substantially as shown and described.

LEOPOLD KAHN.
